SPEED REGULATING APPARATUS FOR USE WITH
AN INTERNAL COMBUSTION ENGINE

George W. Cornelius, Covina, Calif.

Application March 5, 1954, Serial No. 414,448

12 Claims. (Cl. 123—103)

The present invention relates generally to internal combustion engines and more particularly to novel speed regulating apparatus for use therewith.

There have been heretofore proposed several types of governing devices for maintaining the rotational speed of an internal combustion engine between predetermined limits. The majority of such devices have incorporated rotating weights and are generally termed "fly-ball" governors. Such devices have not proven to be entirely satisfactory in operation, especially where the engine speed must be very accurately maintained within close limits, e. g., where the engine is utilized to drive an electric generator. Under such conditions, the engine generally tends to "hunt," first rotating at too great a speed and then suddenly dropping to a too-low speed. The conventional speed-regulating apparatus is, moreover, difficult to install and requires frequent servicing. Additionally, the conventional speed-regulating apparatus requires a troublesome belt and pulley arrangement for transferring power from the engine thereto, which transfer involves a decided power loss.

It is a major object of the present invention to provide a novel improved speed-regulating apparatus for use with an internal combustion engine.

Another object of the invention is to provide apparatus of this nature which will accurately maintain the speed of an engine between narrow predetermined limits even though the work load of the engine varies between no load and full load.

A further object is to provide speed-regulating apparatus of the aforescribed nature which utilizes the engine's exhaust pressure as a sensing medium for controlling the speed of the engine.

Yet another object of the present invention is to provide apparatus of the aforescribed nature which is extremely simple of design, has no rapidly moving parts and is rugged of construction, whereby it may have a long, trouble-free service life.

It is a further object to provide speed-regulating apparatus which may be readily installed on an internal combustion engine by even a semi-skilled worker, and which may be adjusted without any special tools or training by such worker.

An additional object of the invention is to provide speed-regulating apparatus especially adapted for use with an internal combustion engine having a constant work load, which apparatus is extremely compact, light in weight and sturdy.

Another object is to provide speed-regulating apparatus which may be installed on existing conventional internal combustion engines without requiring other than minor alterations thereof, and which may be easily incorporated as original equipment on new engines during the latter's manufacture.

It is an additional object of the invention to provide speed-regulating apparatus which may be fabricated of readily obtainable material by simple manufacturing

2

processes, and hence may be sold at a comparatively low price.

Yet another object is to provide speed-regulating apparatus, the utilization of which does not effect a power loss for the engine whereon it is installed.

These and other objects and advantages of the present invention will become apparent from the following detailed description when taken in conjunction with the appended drawings, wherein:

10 Figure 1 is a side elevational view showing an internal combustion engine whereon is mounted a preferred form of speed-regulating apparatus, embodying the present invention;

15 Figure 2 is an enlarged, partly sectional, view of said speed-regulating apparatus;

Figure 3 is a fragmentary view of a detail of said speed-regulating apparatus;

20 Figure 4 is a further enlarged central vertical sectional view of a modification of said speed-regulating apparatus;

25 Figure 5 is a perspective view, showing another internal combustion engine whereon is mounted a special form of speed-regulating apparatus embodying the present invention;

30 Figure 6 is an enlarged central vertical sectional view of a major unit of said special form of speed-regulating apparatus; and

Figure 7 is an enlarged central vertical sectional view of an alternate form of speed-regulating apparatus which may be utilized in conjunction with the engine shown in Figure 5.

General arrangement

Referring to the drawings, and particularly to Figure 35 1 thereof, there is shown a conventional internal combustion engine E mounted on a base 20, which engine mounts a carburetor 22 upon an intake manifold 24. The carburetor 22 includes a throttle arm 26. An exhaust manifold 28 is disposed below the intake manifold

40 24 and is in communication with an exhaust pipe 30. The speed-regulating apparatus S embodying the present invention is mounted in the vicinity of the carburetor 22 and the intake and exhaust manifolds, and includes

45 an actuating housing A and a control housing C. A rod 32 mounted for reciprocal movement relative to the actuating housing A is connected to the lower end of the throttle arm 26 by a link 34 for controlling the action thereof. A manual overcontrol device for the throttle arm 26 is likewise provided in the form of a cable 36 shown attached to the upper end thereof.

Construction of Figures 2 and 3

More particularly, referring to Figures 2 and 3, the 55 throttle arm 26 is rigidly secured to a pivot pin 38 which is journaled by the side walls of the carburetor throat cylinder 40. A throttle valve 42 is affixed to the pivot pin 38, whereby rotation of the throttle arm 26 will effect concurrent rotation of the pivot pin 38 and thereby open and close the throttle valve 42. In this manner, the amount of air (and hence fuel), entering the intake manifold 24 may be varied. It will be apparent that this arrangement is conventional internal combustion engine practice.

Actuator housing A

The actuating housing A defines a chamber 44 wherein is mounted a pressure-responsive wall 48 that takes the form of a flexible metallic diaphragm. The mid-portion of this diaphragm 46 is rigidly affixed to the end of the rod 32 opposite the link 34 by a keeper 47. Hence, movement of the diaphragm 46 will effect concurrent movement of the throttle arm 26 and the throttle valve 42.

The actuating housing A preferably consists of two sections, designated 48 and 50 respectively, that are rigidly joined by a plurality of bolts 52. Section 48 includes a guide collar 54 which slidably supports the rod 32 for reciprocal movement toward and away from the carburetor 22. An air vent 55 is also formed in section 48. Section 50 is formed with a cylindrical spring enclosure 56 aligned with and coaxial to the chamber 44. This spring enclosure 56 is formed with internal threads 58 for threadably engaging the complementary threads 60 of a closure member 62. This closure member 62 is formed with a bore 64 wherein is disposed a set screw 66 that includes a spring backing element 68. The spring backing element 68 may be formed with threads 70 that are engaged with internal threads 58. A lock nut 72 is mounted outwardly of closure member 62. An O-ring 74 and a resilient washer 75 may be provided for sealing the bore 64 and the outer end of the spring enclosure 56, respectively. A helical compressing spring 76 is interposed between the spring backing element 68 and the rod keeper 47 so as to normally bias the rod toward the carburetor 22. In this manner, the throttle valve 42 will normally be urged toward an open position as indicated in Figure 2. The effective length of the spring 76 may be adjusted by means of the set screw 66.

One side of the actuating housing section 50 is formed with a treaded bore 80 adapted to receive an elbow 82. This elbow 82 is connected to the upper end of a main conduit 84; the opposite end of this conduit being connected to a fitting 86. The fitting 86 is threaded within a bore 88 which leads to the throat portion 90 of a venturi tube V disposed in the engine's exhaust line; the upper end of this tube V being secured to the exhaust manifold 28 by bolt and nut combinations 92. With this arrangement, during operation of the engine E, the vacuum created in the venturi tube's throat 90 will be communicated through main conduit 84 to the left side of the chamber 44. Such vacuum tends to cause the diaphragm 46 to flex toward the left and thereby move the rod 32 to the left, which rod movement in turn closes the throttle valve 42.

Control housing C

The control housing C defines a chamber 94 wherein is mounted a flexible metal diaphragm 96. The mid-portion of this diaphragm is rigidly affixed to a piston 98 slidably mounted within a bore 100. The piston carries an O-ring 101 for providing a seal with this bore 100. The upper end of the piston 98 rigidly mounts an upstanding tapered barrier element or needle 102 for reciprocation relative to an orifice 104. The needle carries an O-ring 105 for providing a seal with a guide bore 106 that encompasses its lower portion. An air vent 107 is formed below the orifice 104. The opposite side of the orifice is in communication with the main conduit 84 by means of an auxiliary conduit 108. The upper end of the bore 100 is in communication with the intake manifold 24 by means of a length of tubing 110. The upper surface of the diaphragm 96 is in communication with the pressure in the exhaust manifold 28 by means of another length of conduit 112, while the underside of this diaphragm is in communication with the throat 90 of the venturi tube V by means of yet another length of tubing 114.

As in the case of the actuator housing A, the control housing C consists of two sections, designated 116 and 118, respectively, that are rigidly joined by a plurality of bolts 120. The lower section 118 includes a spring enclosure 120 formed with internal threads 122 for threadably engaging a closure member 124. This closure member 124 is formed with a bore 126 wherein is disposed a set screw 128 that includes a spring backing element 130. The spring backing element may include threads engagable with internal threads 122. O-ring 131 and a resilient washer 132 may be provided for sealing the bore 126 and

the lower end of the housing, respectively. A lock nut 133 is mounted outwardly of closure member 124. A helical compression spring 134 is interposed between the spring backing element 130 and the underside of the diaphragm 96 so as to normally bias the diaphragm, piston 98 and needle 102 upwardly. The effective length of the spring 134 may be adjusted by means of the set screw 128.

Operation of Figures 2 and 3

During operation of the engine E, the vacuum created in the venturi tube's throat 90 and the positive pressure existing within the exhaust manifold 28 tends to flex the diaphragm 96 downwardly. Meanwhile, the intake manifold vacuum tends to draw the piston 98 (and hence the diaphragm) upwardly. The spring 134 likewise biases the diaphragm upwardly. It should be particularly observed that the area of the piston relative to the area of the diaphragm is such that at no-load, constant-speed engine operation, the intake manifold vacuum tends to draw the piston upwardly with substantially the same amount of force that the vacuum created within the throat 90 tends to draw the diaphragm downwardly. Additionally, at a no-load constant-speed engine operating condition the downwardly-acting force exerted upon the upper surface of the diaphragm by the exhaust manifold pressure entering the control housing C through conduit 112 is balanced by the upward force of the spring 134. Hence, at a no-load, constant-speed engine operating condition, the diaphragm will be maintained in its position of Figure 2, in which position the needle 102 blocks the orifice 104 so as to prevent the flow of atmospheric air into the auxiliary conduit 108. Inasmuch as no atmospheric pressure may enter the left side of the actuator chamber 44 during no-load, constant-speed engine operation, the diaphragm 46 will be caused to flex to the left during such operation; the rod maintaining the throttle valve 42 in a near-closed position. The exact throttle valve position may be controlled by adjustment of the set screw 66, such adjustment varying the force being exerted by the spring 76. The position of the throttle valve determines the speed of the engine.

As a load is applied to the engine, the intake manifold vacuum decreases, thereby reducing the upward force acting upon the upper surface of the piston 98; the vacuum in the venturi throat 90 increases, thereby increasing the suction being exerted upon the underside of the diaphragm 96; and, the positive pressure within the exhaust manifold increases, thereby increasing the downward force being exerted upon the upper surface of the diaphragm. Accordingly, the diaphragm, piston and needle will be moved downwardly permitting atmospheric pressure to pass through the orifice 104, conduits 108 and 84, and into the actuating chamber 44. This atmospheric pressure reduces the effectiveness of the vacuum created by the venturi throat 90 and transmitted to the chamber by the main conduit 84. Accordingly, the spring 76 is free to urge the diaphragm (and hence the rod 32) to the right so as to open the throttle valve 42 in direct relation to the increased load applied to the engine.

In order to demonstrate the relationship between the intake manifold vacuum, the venturi throat vacuum and the exhaust manifold pressure as the engine load is increased while its speed remains constant, there appears below a chart representing an actual test of an engine equipped with speed-regulating apparatus of the type disclosed herein. The engine tested was coupled to an electric generator, the watt output of which was increased to load the engine. The intake manifold vacuum was measured in inches of mercury, and the exhaust vacuum and manifold pressures were measured in inches of water. The engine speed remained at 1800 R. P. M.

equal the force of the exhaust gas pressure tending to close the needle valve; such pressure acting against the diaphragm 168'. The air-fuel ratio so established will thereafter remain substantially constant even though the engine is kept in operation through a progressive rise in altitude. During such altitude gain, the exhaust gas pressure falls off due to rarefied air conditions. However, as this occurs, the spring 176' will move the needle valve to a more fully opened position so as to automatically meter additional fuel to the engine. Such additional fuel allows the engine to maintain its original constant-speed and constant-load.

It will be apparent that either of the speed-regulating apparatus R and R' are adapted for use in controlling the ratio of air-to-fuel rather than fuel-to-air. This may be accomplished by placing a restricting means such as a throttle valve in the engine's intake tube 156, and controlling the position of such valve by either of these speed-regulating apparatus. Alternately, these apparatus may be utilized to control both the fuel-to-air ratio and the air-to-fuel ratio.

While there have been shown and described hereinbefore certain embodiments of the present invention, it will be apparent that various changes and modifications thereof may be made without departing from the spirit of the invention and the scope of the following claims.

I claim:

1. Speed regulating apparatus for use with an internal combustion engine, said engine having valve means for varying the flow of fuel thereto, said engine also having an exhaust line, comprising: a chamber; a flexible diaphragm extending across said chamber; means connecting said diaphragm to said valve means; spring means normally urging said valve means toward an open position; and, conduit means for connecting said chamber with said exhaust line whereby pressure created therein during operation of said engine will be communicated to one side of said diaphragm so as to at least partially offset the force of said spring means.

2. Speed regulating apparatus for use with an internal combustion engine, said engine having valve means for varying the flow of fuel thereto, said engine also having an exhaust line, comprising: a chamber; a pressure-responsive wall in said chamber, one side of said wall being exposed to the atmosphere; means operatively connecting said wall and said valve means; biasing means normally urging said valve means toward an open position; and, conduit means for connecting the opposite side of said wall to said exhaust line whereby pressure created therein during operation of said engine will tend to oppose the force exerted by said biasing means.

3. Speed regulating apparatus for use with an internal combustion engine, said engine having valve means for varying the flow of fuel thereto, said engine also having an exhaust line, comprising: a chamber; a flexible diaphragm extending across said chamber, one side of said diaphragm being exposed to the atmosphere; rod means operatively connecting said diaphragm and said valve means; spring means acting upon said rod means to normally bias said valve means toward an open position; and, conduit means for connecting said chamber with said exhaust line whereby pressure created therein during operation of said engine will be communicated to the opposite side of said diaphragm so as to at least partially offset the force of said spring means.

4. Speed regulating apparatus for use with an internal combustion engine, said engine having valve means for varying the flow of fuel thereto, said engine also having an exhaust line wherein is disposed venturi means having a throat, comprising: a chamber; a pressure-responsive wall in said chamber; biasing means tending to move said valve means into an open position; means operatively connecting said wall and said valve means; and, conduit means connecting said chamber with the throat of said venturi whereby negative pressure created therein during

operation of said engine will be communicated to one side of said wall so as to at least partially offset the force of said biasing means.

5. Speed regulating apparatus for use with an internal combustion engine, said engine having valve means for varying the flow of fuel thereto, said engine also having an exhaust line wherein is disposed venturi means having a throat, comprising: a chamber; a pressure-responsive wall in said chamber, one side of said wall being exposed to atmospheric pressure; means operatively connecting said wall and said valve means; biasing means normally urging said valve means toward an open position; conduit means for connecting said chamber to the throat of said venturi so as to expose the opposite side of said wall to the negative pressure created in said throat during operation of said engine; a second chamber; a second pressure-responsive wall in said second chamber, one side of said wall being in communication with said throat and the opposite side thereof being in communication with said exhaust line at one side of said venturi; a piston coaxially mounted by said second wall, said piston being slidably disposed in a bore that forms an axial continuation of said second chamber, and the end of said bore remote from said second wall being in communication with the intake manifold pressure of said engine; an orifice having one of its sides exposed to the atmosphere and the other side in communication with said conduit means; and, a tapered barrier element mounted by said piston for reciprocal movement within said orifice.
- 10 6. Speed regulating apparatus for use with an internal combustion engine, said engine having valve means for varying the flow of fuel thereto, said engine also having an exhaust line wherein is disposed venturi means having a throat, comprising: a chamber; a pressure-responsive wall in said chamber, one side of said wall being exposed to atmospheric pressure; means operatively connecting said wall and said valve means; biasing means normally urging said valve means toward an open position; conduit means for connecting said chamber to the throat of said venturi so as to expose the opposite side of said wall to the negative pressure created in said throat during operation of said engine; a second chamber that includes a coaxial bore portion at one of its ends; a second pressure-responsive wall in said second chamber, one side of said wall being in communication with said throat and the opposite side thereof being in communication with said exhaust line at one side of said venturi; a piston coaxially mounted by said second wall for reciprocal movement within said bore, the end of said bore remote from said second wall being in communication with the intake manifold pressure of said engine, and the area of said piston relative to that of said second wall being such that at no-load, constant-speed operation of said engine the oppositely-acting forces applied to said piston and said second wall will be substantially equal; second biasing means for urging said second wall toward said bore, the strength of said biasing means at no-load, constant-speed operation of said engine being substantially equal to the oppositely-acting force being exerted upon said second wall by the pressure existing in said exhaust line; an orifice having one of its sides exposed to the atmosphere and the other side in communication with said conduit means; and, a tapered barrier element mounted by said piston for reciprocal movement within said orifice.
- 15 7. Speed regulating apparatus for use with an internal combustion engine, said engine having valve means for varying the flow of fuel thereto, said engine also having an exhaust line wherein is disposed venturi means having a throat, comprising: a chamber; a flexible diaphragm extending across said chamber; means operatively connecting said diaphragm to said valve means; spring means normally urging said valve means toward an open position; conduit means for connecting said chamber to the throat of said venturi so as to expose the opposite side of said wall to the negative pressure created

Load, Watts	Intake Manifold Press.	Throat Venturi Press.	Manifold Exhaust Press.
0	-12.6	-7.8	10
1,000	-11.9	-9	11
2,000	-11	-10.3	12.6
3,000	-10.3	-12	14.6
4,000	-9.2	-13.2	16
5,000	-8.1	-15.2	19
6,000	-7.1	-17.3	21.6
7,000	-6.2	-18.8	25.4
8,000	-5.4	-20.6	28
9,000	-4.4	-23	31.4
10,000	-3.6	-25.4	34.8
11,000	-3	-27.3	37.4

It will be noted by a study of the above chart that the three pressures vary in direct relationship to the load being applied to the engine when the correct adjustments are made to establish the no-load speed at the desired value. It should also be noted that the rate of opening of the throttle valve 42 may be varied from one engine to another either by varying the relative areas of the piston 98 and the diaphragm 96, or by the use of an air bleed at the upper end of the bore 100, or below the diaphragm 96, as the situation may require.

Construction of Figure 4

Referring now to Figure 4, there is shown a modified form of control housing C'. This control housing C' is generally similar to the aforescribed control housing C, having a flexible metal diaphragm 96', which rigidly mounts a piston 98' slidably mounted within a bore 100'. This piston 98' mounts a tapered needle 102' for controlling the amount of atmospheric air entering the auxiliary conduit 108 through orifice 104'. The upper end of the bore 100' is in communication with the engine's intake manifold by means of a length of tubing 110'. The upper surface of the diaphragm 96' is in communication with the pressure in the engine's exhaust manifold by a conduit 112'. The underside of this diaphragm is not connected to the throat of the venturi tube, however, as in the case of the control chamber C of Figure 2, but instead, it is exposed to atmospheric pressure by means of a restricting orifice 140. It should be noted that the diaphragm 96' is not spring-urged upwardly in the modified control housing C'.

Operation of Figure 4

In operation, at idling and at no-load, constant-speed engine operating conditions, the intake manifold pressures will exert greater suction or upward force upon the upper surface of the piston 98' than the downwardly acting force exerted by the exhaust pressure upon the upper surface of the diaphragm 96'. Hence, the needle 102' will block off any flow of air through the orifice 104'. The restricting orifice 140 restrains oscillation of the diaphragm 96' due to impulses from the intake and exhaust manifolds. As the engine load is increased, the intake manifold vacuum decreases while the exhaust pressure increases (see above chart). Accordingly, the diaphragm 96', piston 98', and needle 102' will be moved downwardly permitting atmospheric pressure to pass through the orifice 104' and auxiliary conduit 108. Such atmospheric pressure reduces the effectiveness of the vacuum existing in the chamber 4 of the actuator housing A.

It should be especially observed that the utilization of the venturi tube V in the engine's exhaust line smooths out or "tunes" the exhaust gas surges. The smoothing out of such surges appreciably reduces the back pressure of exhaust gases and hence contributes to the engine's efficiency.

Construction of Figures 5 and 6

Referring now to Figure 5, there is shown a conventional two-cycle engine T, whereon is mounted another

form of speed-regulating apparatus R embodying the present invention. This engine T is especially adapted for use under constant-speed, constant-load conditions at various altitudes. The engine T includes an exhaust pipe

5 150 wherein is disposed a venturi section 152 that includes a throat portion 154. Liquid fuel enters the air intake tube 156 of the engine through a fuel line 158. The amount of fuel entering tube 156 is controlled by a needle valve 160, which needle valve is mounted for axial

10 movement relative to a regulating orifice 162.

As shown in Figure 6, the speed-regulating apparatus R includes a two-piece housing 164 which defines a chamber 166 wherein is mounted a pressure-responsive

15 diaphragm 168 rigidly mounts the end of the needle valve 160 opposite the regulating orifice 162. An adjusting rod 170 is threadably mounted by the diaphragm 168 so as to form an axial continuation of the needle valve

20 160. The end of the adjusting rod 170 opposite the diaphragm is threadably secured to a nut element 172, the underside of which abuts a spring retaining washer 174.

25 A helical compression spring 176 is interposed between the underside of washer 174 and a radially inwardly extending lip 178 formed on the housing 164. A

closure member 180 is threadably carried by the housing, which closure member is removable so as to permit adjustment of the effective length of the spring 176. With this arrangement, the spring 176 normally biases the needle valve 160 out of the regulating orifice 162, i. e., towards an open position.

The side of the diaphragm 168 opposite the spring 176 is connected to the throat portion 154 of the venturi 152 by a conduit 182. The opposite side of the diaphragm is in communication with the atmosphere by means of a

30 35 vent hole 184. An O-ring 186 carried by the needle valve 160 seals the bore 188 between the chamber 166 and fuel passage 190.

Operation of Figures 5 and 6

40 In operation, with the engine T operating at constant-speed and constant-load, the force of the spring 176 tending to open the needle valve 160 may be adjusted to equal the force of the exhaust gas vacuum tending to close the needle valve; such vacuum acting against the

45 45 diaphragm 168. The air-fuel ratio so established will thereafter remain substantially constant even though the engine T is kept in operation through a progressive rise in altitude. During such rise in altitude, the exhaust gas vacuum falls off due to rarefied air conditions. However, as this occurs, the spring 176 will move the needle

50 55 valve to a more fully opened position, so as to automatically meter additional fuel to the engine. Such additional fuel will allow the engine to maintain its original constant-speed and constant-load.

Construction of Figure 7

Referring now to Figure 7, there is shown an alternate form of speed-regulating apparatus R', which may be utilized with the two-cycle engine T in place of the speed-regulating apparatus R' described hereinbefore.

60 65 This apparatus R' is substantially similar to apparatus R, except that an air vent 200 is formed in the housing 164' at the side of the diaphragm 168' opposite the spring 176', and the other side of the diaphragm 168' is in communication with the exhaust pipe (not shown) of the engine by means of a conduit 202. It should be particularly observed that such exhaust pipe is not formed

65 70 with a venturi section in this case, but instead positive exhaust gas pressure is adapted to enter chamber 166' through the conduit 202.

Operation of Figure 7

In operation, with the engine T operating at constant-speed and constant-load, the force of the spring 176' tending to open the needle valve 160' may be adjusted to

in said throat during operation of said engine; a second chamber that includes a coaxial bore portion at one of its ends; a second flexible diaphragm extending across said second chamber, one side of said diaphragm being in communication with said throat and the opposite side thereof being in communication with said exhaust line at one side of said venturi; a piston coaxially mounted by said second diaphragm for reciprocal movement within said bore, the end of said bore remote from said diaphragm being in communication with the intake manifold of said engine; an orifice having one of its sides exposed to the atmosphere and the other side in communication with said conduit means; and, a tapered barrier element mounted by said piston for reciprocal movement within said orifice.

8. Speed regulating apparatus for use with an internal combustion engine, said engine having valve means for varying the flow of fuel thereto, said engine also having an exhaust line wherein is disposed venturi means having a throat, comprising: a chamber; a flexible diaphragm extending across said chamber; means operatively connecting said diaphragm to said valve means; spring means normally urging said valve means toward an open position; conduit means for connecting said chamber to the throat of said venturi so as to expose the opposite side of said wall to the negative pressure created in said throat during operation of said engine; a second chamber that includes a coaxial bore portion at one of its ends; a second flexible diaphragm extending across said second chamber, one side of said diaphragm being in communication with said throat and the opposite side thereof being in communication with said exhaust line at one side of said venturi; second spring means normally urging said second wall toward said bore, the strength of said spring means at no-load, constant-speed operation of said engine being substantially equal to the oppositely-acting force being exerted upon said second diaphragm by the pressure from said exhaust line; a piston coaxially mounted by said second diaphragm for reciprocal movement within said bore, the end of said bore remote from said diaphragm being in communication with the intake manifold of said engine; and the area of said piston relative to that of said second diaphragm being such that at no-load, constant-speed operation of said engine the oppositely-acting forces applied to said piston and to said second diaphragm will be substantially balanced; an orifice having one of its sides exposed to the atmosphere and the other side in communication with said conduit means; and, a tapered barrier element mounted by said piston for reciprocal movement within said orifice.

9. Speed regulating apparatus for use with an internal combustion engine, said engine having valve means for varying the flow of fuel thereto, said engine also having an exhaust line wherein is disposed venturi means having a throat, comprising: an actuator housing defining a coaxial chamber and spring enclosure; a chamber; a flexible diaphragm extending across said chamber; means operatively connecting said diaphragm to said valve means; rod means operatively connecting said diaphragm and said valve means; a closure for the end of said spring enclosure remote from said diaphragm; a helical compression spring in said enclosure and chamber that acts upon said rod means so as to normally bias said valve means toward an open position; conduit means for connecting said chamber with the throat of said venturi whereby negative pressure created therein during operation of said engine will be communicated to the opposite side of said diaphragm so as to at least partially offset the force of said spring; a control housing defining a chamber, a coaxial bore at one end of said chamber and a coaxial spring enclosure at the opposite end thereof; a second flexible diaphragm dividing the latter chamber; means

for connecting the end of said bore remote from said diaphragm to the intake manifold of said engine; a coaxial piston rigidly mounted by said diaphragm for reciprocal movement within said bore; a second helical compression spring in the enclosure and chamber of said central housing for biasing said diaphragm toward said bore; means for connecting the side of said chamber adjacent said bore with said exhaust line at one side of said venturi; means for connecting the opposite side of said chamber with the throat of said venturi; an orifice formed in said control housing having one of its sides exposed to the atmosphere and its other side in communication with said conduit means; and, a tapered needle mounted by said piston for reciprocal movement within said orifice.

10. Speed regulating apparatus for use with an internal combustion engine that is adapted to operate under constant-speed and constant-load conditions at various altitudes, said engine having a needle valve for controlling the flow of fuel thereto, said engine likewise having an exhaust line comprising: a chamber; a flexible diaphragm extending across said chamber, one side of said diaphragm being exposed to the atmosphere; means connecting said diaphragm and said needle valve; spring means constantly biasing said needle valve toward an open position; and conduit means for connecting said chamber with said exhaust line whereby pressure created therein during operation of said engine will be communicated to the opposite side of said diaphragm so as to at least partially offset the force of said spring means.

11. Speed regulating apparatus for use with an internal combustion engine that is adapted to operate under constant-speed and constant-load conditions at various altitudes, said engine having a needle valve for controlling the flow of fuel thereto; said engine likewise having an exhaust line comprising: a housing defining a chamber; a flexible diaphragm extending across said chamber and having its midportion secured to said needle valve; a helical compression spring interposed between said diaphragm and said housing for normally biasing said needle valve toward an open position; an adjusting rod interposed between said diaphragm and said housing for controlling the force exerted by said spring; a vent formed in said housing placing one side of said diaphragm in communication with the atmosphere; and conduit means connecting the opposite side of said diaphragm with said exhaust line whereby pressure created therein during operation of said engine will act against said diaphragm so as to at least partially offset the force of said spring.

12. Speed regulating apparatus for use with an internal combustion engine, said engine having valve means for varying the flow of fuel thereto, said engine also having an exhaust line wherein is disposed venturi means having a throat, comprising: a chamber; a diaphragm disposed in said chamber, one side of said diaphragm being exposed to atmospheric pressure; spring means normally urging said valve means toward an open position wherein a maximum amount of fuel will be admitted to said engine; and conduit means for connecting said chamber with the throat of said venturi whereby negative pressure created therein during operation of said engine will be communicated to the opposite side of said diaphragm so as to at least partially offset the force of said biasing means.
